(57) **CLAIM**

The ornamental design for a light emitting diode headset, as shown and described.

DESCRIPTION

FIG. 1 is a perspective view of the light emitting diode headset;

FIG. 2 is a front elevation view thereof in an example orientation;

FIG. 3 is a front elevation view thereof;

FIG. 4 is a back elevation view thereof;

FIG. 5 is a top elevation view thereof;

FIG. 6 is a bottom elevation view thereof;

FIG. 7 is a right side view thereof; and,

FIG. 8 is a cross-sectional perspective view taken substantially along lines 8-8 of FIG. 1.

The portion of the light emitting diode headset depicted in broken lines form no part of the claimed design. The hashed lines on the cross-sectional view of FIG. 8 should not be read to show or claim any internal structure.
